Application April 18, 1950, Serial No. 9,286

Term of patent 3½ years

(Cl. D48—20)

To all whom it may concern:

Be it known that we, Leo Moss and Philip Ferrara, both citizens of the United States, residing at Forest Hills, New York, and Brooklyn, New York, respectively, in the counties of Queens and Kings, respectively, both in the State of New York, have invented a new, original, and ornamental Design for a Table Lamp, of which the following is a specification, reference being had to the accompanying drawing, forming a part thereof.

In the drawing:

Fig. 1 is a front elevational view of a table lamp, showing my new design;

Fig. 2 is a rear elevational view; and

Fig. 3 is a side elevational view of the same.

We claim:

The ornamental design for a table lamp, as shown.

LEO MOSS.
PHILIP FERRARA.
